US0D1021892S

(12) **United States Design Patent** (10) Patent No.: **US D1,021,892 S**
(45) Date of Patent: ** Apr. 9, 2024

(54) **DISPLAY FOR ELECTRONIC COMMUNICATION DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Scott A. Myers**, San Francisco, CA (US); **David A. Pakula**, San Francisco, CA (US); **Rasamy Phouthavong**, Campbell, CA (US); **Matthew Dean Rohrbach**, San Francisco, CA (US); **Peter Russell-Clarke**, San Francisco, CA (US); **Benjamin Andrew Shaffer**, San Jose, CA (US); **Ashutosh Y. Shukla**, Santa Clara, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/759,794**

(22) Filed: **Nov. 25, 2020**

CLAIM

The ornamental design for a display for electronic communication device, as shown and described.

DESCRIPTION

FIG. 1 is a front perspective view of a display for electronic communication device showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the figures show portions of the display for electronic communication device that form no part of the claimed design.

The oblique shade lines in the figures show transparency or translucency.
